(57) **CLAIM**

We claim the ornamental design for an air dry dryer, as shown and described.

DESCRIPTION

FIG. 1 is a perspective view of an air dry dryer of the new design;

FIG. 2 is a first side view of the air dryer of FIG. 1;

FIG. 3 is a second side view of the air dryer of FIG. 1;

FIG. 4 is a third side view of the air dryer of FIG. 1;

FIG. 5 is a fourth view of the air dryer of FIG. 1;

FIG. 6 is a top view of the air dryer of FIG. 1; and,

FIG. 7 is a rear view of the air dryer of FIG. 1.

The portions of the Figures shown in phantom lines are not part of the claimed design and are for illustration only.
